SASH PULLEY

Application filed February 29, 1928. Serial No. 258,080.

Our invention relates to a window sash pulley and particularly to the bearing therefor, to the end that it will be substantially noiseless during the operation of raising or 5 lowering the window sash, and will also be of such construction that it will be extremely durable and adapted particularly for the purpose designed.

The primary object of this invention is to 10 provide means whereby a fibrous bushing forming the core of the pulley may be allowed to expand through exposure to moisture or weather conditions, and still during such expansion turn freely on its axis or sup- 15 porting pin.

A further object is to provide a sash pulley of very simple construction, and one that can be manufactured and sold at a comparatively small cost.

20 Other objects of the invention will appear from the following detailed description.

In the accompanying drawing forming part of this specification,

Figure 1 is a sectional view through a pul- 25 ley and its housing embodying our invention and taken on a section line 1—1 of Figure 2;

Figure 2 is a sectional view taken on section line 2—2 of Figure 1;

Figure 3 is a detailed sectional view of the 30 sheave removed from the housing; and

Figure 4 is a detailed view of the hub of the sheave showing the orifice centrally arranged therein.

In the drawing, 2 represents the housing 35 or casing of the pulley adapted to fit into the recess in the window jamb, as usual in devices of this kind, and having the usual flanges 3 by means of which the housing is secured.

The sheave which we prefer to use in this 40 housing is preferably of cast metal and comprises a hub 4 having a peripheral flange 5 terminating in flaring walls 6 between which a seat 7 is formed for the sash cord, as usual in devices of this kind. The hub 4 has a bore 45 or orifice 8 extending therethrough and preferably this orifice is rectangular in form as shown in the drawing, provided with four walls which bound the orifice, but the number of these walls may be increased or de- 50 creased as preferred and still be within the

scope of the invention. For convenience in this case we have used the rectangular construction as shown within the orifice and preferably about midway between the ends of the hub we provide a recess 9 formed in the inner face of each wall and extending continuously around the orifice. This recess may have a curved bottom as shown in the drawing, or it may be flat and of substantially the same width at the bottom as it is at the surface of the orifice. The size and shape, however, of this recess is immaterial. The walls of the orifice on each side of the recess will, as indicated in Figure 3, preferably come to a rather sharp edge or shoulder and within the orifice we arrange a bushing 10, preferably of suitable fibrous material that is adapted to be and preferably is impregnated with a lubricating agent. The pores of the fibrous material become filled with this lubricant so that the bushing will at all times have a substantially anti-friction bearing on the pin or axis of the pulley sheave and insure freedom of revolution of the sheave without noise and with a minimum of wear. The moisture to a considerable extent is driven out of the bushing either before it is impregnated with the lubricating agent, or subsequent to that operation, and when the bushing is firmly held within the orifice of the pulley sheave, ex- 70 pansion, due to moisture or any weather conditions, may enlarge the bushing to such an extent that it will grip the surface of the axle or supporting pin and interfere with the free rotation of the sheave thereon. By providing the recess in the inner wall of the sheave hub, we provide for freedom of outward movement of the bushing during expansion, the swelling of the wood following naturally the direction of least resistance, and the re- 75 cess is of sufficient width and depth to allow the bushing to swell outwardly and bear firmly against the inner surface of the sheave hub, and at the same time, turn freely on the axle or supporting pin of the sheave. This swelling or expansion of the bushing will also lock it in the hub and positively prevent longitudinal movement and any possibility of the annoying clicking metallic sound which 80 results from the contact of metal upon metal. 85

The ends of the bushing protrude beyond the sides of the sheave as shown in Figure 2, and it will not be possible for the sheave to come in direct contact with the housing, and the 5 sheave will also at all times be separated by the bushing from the pin or axle upon which the sheave turns. It will be understood that any suitable fibrous material capable of absorbing or having its pores impregnated with 10 a lubricating substance, may be used in the construction of the bushing. The outer surface of the bushing is formed to fit the walls of the orifice, in this particular case the bushing being substantially square in cross section 15 to fit the correspondingly shaped orifice in the hub of the sheave. It will be understood, however, that whenever the form of the orifice is changed, the shape of the bushing may be correspondingly altered so that it will fit 20 snugly within the orifice and the comparatively sharp edges of the recess in the hub will tend to dig into the surface of the bushing and hold it against premature movement in the orifice.

25 A considerable gap will be formed between the bottom of the recess and the wall of the bushing which will allow expansion of the bushing under certain conditions, and when the wall of the bushing has become expanded 30 within the recess, it is evident that the bushing will be firmly locked against movement in either direction in the orifice, and this locking effect, due to the expansion of the bushing in the recess, will positively prevent 35 endwise movement of the bushing, and as the ends of the bushing project outwardly on each side beyond the wall of the sheave and contact with the inner surface of the housing, it is evident that there can be no 40 contact of metal upon metal in the operation of the pulley and hence the movement of the sheave in raising and lowering a window, will be substantially noiseless.

The bushing has a bore 11 extending there- 45 through and a pin 12 forming the axis of the sheave is inserted through holes in the hous- ing and through the circular bore of the bushing 10, and when the ends of the pin 12 are upset as indicated in Figure 2, the 50 bushing and the sheave will be firmly held in the walls of the housing, but the sheave and its bushing may turn freely on the pin with the lubricant impregnated ends of the bushing contacting with the inner faces of 55 the housing and producing a dead, muffled sound, if any sound at all, instead of the usual metallic click that accompanies the contact of one piece of metal with another.

We claim as our invention:

60 A sash pulley comprising a housing, a sheave having a hub fitting within said hous- ing and provided with an orifice, a bushing of fibrous material fitting within said orifice and having a bore therethrough, a member 65 mounted in said housing and passing through

the bore of said bushing and whereon said bushing and sheave are adapted to turn free- 70 ly, the inner wall of said hub around said orifice having a groove or recess formed therein intermediate to the ends of the ori- fice and extending through a substantial por- 75 tion of the inner surface of said hub, said groove being adapted to allow sufficient out- ward expansion of said bushing to insure continual freedom of revolution of said sheave and bushing on said member when said bushing is exposed to moisture.

In witness whereof, we have hereunto set our hands this 14th day of February, 1928.
